(57) **CLAIM**

The ornamental design for an integral mirror and weather station, as shown and described.

DESCRIPTION

FIG. 1 is a perspective view of the integral mirror and weather station.

FIG. 2 is a front view of the integral mirror and weather station.

FIG. 3 is a rear view of the integral mirror and weather station.

FIG. 4 is a left side elevation view of the integral mirror and weather station.

FIG. 5 is a right side elevation view of the integral mirror and weather station.

FIG. 6 is a top view of the integral mirror and weather station; and,

FIG. 7 is a bottom view of the integral mirror and weather station.

The surface shading illustrated in the drawings is provided merely to highlight the contour of design; it is not intended to be illustrative of texture or gloss and forms no part of the claimed design.

The portions of the integral mirror and weather station shown in broken lines form no part of the claimed design.
